SAUSAGE LINKING

William James McCue, Chicago, Ill., assignor to
 Industrial Patents Corporation, Chicago, Ill.,
 a corporation of Delaware

Application January 30, 1939, Serial No. 253,686

4 Claims. (Cl. 17—45)

This invention relates to a method of treating a stuffed sausage casing.

One of the objects of the invention is to provide a method of arranging a continuous chain of link lengths of sausage during forming of the links, in aligned pairs of links for mounting of a smoking support.

Other objects of the invention will be apparent from the description and claims which follow.

In the smoking of Frankfurter links, it is the practice to suspend pairs of links astride a support with the twisted casing joining the ends of the suspended links rested against the support, or to suspend two of each four links of a chain of links astride a support in the form of a diamond-shaped coil. In accordance with the present invention, a stuffed sausage casing is formed into a continuous chain of links and, at the same time, it is arranged into pairs of links ready for mounting on a smoking support either in the form of pairs of links or in the form of a diamond-shaped coil.

Reference is had to the drawings in which like characters of reference are used to designate similar parts.

Figure 1 is a plan view illustrating one form of the device for carrying out the process of the present invention.

Figure 2 is an end view of the device shown in Figure 1.

Figure 3 is a plan view of a modified form of the device constructed in accordance with the present invention.

Figure 4 is an end view of the device shown in Figure 3.

Figure 5 is a perspective view exemplifying the first step of the method of the present invention in which a stuffed casing is formed into link lengths and in which the formed links are arranged for mounting on a smoking support.

Figure 6 is a perspective view exemplifying the second step of the method of the present invention.

Figure 7 is a perspective view exemplifying the third step of the method of the present invention.

Figure 8 is a perspective view exemplifying the fourth step of the method of the present invention.

Figure 9 is a perspective view exemplifying the fifth step of the method of the present invention.

Figure 10 is a perspective view exemplifying the sixth step of the method of the present invention.

Figure 11 is a view showing the manner of mounting the arranged links astride a smoking support in the form of pairs of links.

Figure 12 is a view showing the manner of mounting the arranged links on a smoking support in the form of a diamond-shaped coil.

Figure 13 is a view showing the links mounted in the manner exemplified in Figure 11.

Figure 14 is a view showing the links mounted in the manner exemplified in Figure 12.

The device shown in Figures 1 and 2 comprises a flat, substantially rectangular surface 1 divided as by surface markers 2 into not less than four adjacent alleys 3 arranged in side by side relationship, each of the alleys 3 being of equal width and of a width substantially equal to the length of the conventional Frankfurter link.

As shown in Figures 1 and 2, surface 1 may comprise a unit sheet of sheet metal material 20 suitably bent on spaced parallel lines to provide raised surface markers 2, such as, for example, upstanding edge flanges 4 and intermediate inverted V markers 5.

As shown in Figures 3 and 4, surface 1 may 25 comprise a unit sheet of sheet metal material provided with raised surface markers 2 comprising, for example, a plurality of rods 6 welded or otherwise rigidly secured to the upper face of surface 1 along spaced parallel lines.

30 The two adjacent alleys 7 and 8 are used in the manner exemplified in Figure 5 for measuring off pairs of link lengths of stuffed casing 9 for forming into links 10 and 11. The method of measuring and forming the links 10 and 11 35 is described and claimed in the copending application of Alonzo Standlee, Serial No. 164,084, filed September 15, 1937, entitled Linking method.

The two remaining alleys, namely, alleys 12 40 and 13 are employed for arranging the formed pairs of links for mounting on smoking support 19 in the manner exemplified in either Figures 11 and 13 or Figures 12 and 14.

45 The method of forming the stuffed sausage casing 9 into pairs of link lengths and arranging the pairs of link lengths in the alleys 12 and 13 for mounting on smoking support 19 in the manner shown in either Figures 11 and 13 or Figures 12 and 14, comprises first measuring the links

50 10 and 11 transversely of the alleys 7 and 8, respectively, in the manner exemplified in Figure 5, and twisting the measured links 10 and 11 in the manner more specifically described in the said Standlee application; second, arranging the 55 pair of link lengths 10 and 11 in longitudinal end

to end relationship transversely of the alleys 12 and 13, respectively, in the manner exemplified in Figure 6; third, forming a second pair of links 14 and 15 in the manner exemplified in Figure 7; fourth, folding the links 14 and 15 against one another and against link 11 transversely of alley 12 in the manner exemplified in Figure 8; fifth, forming a third pair of links 16 and 17 in the manner exemplified in Figure 9; sixth, unfolding the link 15 from against the link 14 10 whence the links 14 and 15 are arranged longitudinally in end to end relationship transversely of the alleys 12 and 13 and adjacent the links 11 and 10, respectively, and simultaneously the links 17 and 16 are arranged longitudinally in 15 end to end relationship transversely of the alleys 12 and 13 and adjacent the links 14 and 15 respectively, in the manner exemplified in Figure 10; and seventh, repeating the cycle until the forming and arranging of the whole of the 20 stuffed casing 9 is completed.

Should it be desired to mount the chain of links astride the smoking support 19 in the form of pairs of links, the smoking support 19 is passed successively beneath the twisted portions 18 of the casing joining the ends of the pairs of links in the manner exemplified in Figure 11, whence the chain of links may be lifted by support 19 from surface 1 and suspended in the manner shown in Figure 13.

Should it be desired to suspend the chain of links in the form of a diamond-shaped coil, smoking support 19 is passed alternately beneath and above the twisted portions 18 joining the ends of the pairs of links in the manner 35 shown in Figure 12, whence the chain of links may be lifted from surface 1 and supported in the manner shown in Figure 14.

I claim:

1. In a method for forming a stuffed sausage casing into a continuous chain of links in which the chain of links is gauged and formed in successive pairs of links, the steps of alternately arranging the successive pairs of links for mounting the chain of links on a smoking support which comprise forming a pair of links and arranging the formed links in longitudinal end to end relationship and longitudinally relative to the line of feed of the stuffed casing, forming the next successive pair of links, folding the last-mentioned pair of links substantially parallel to one another and substantially parallel to the second link of the first-mentioned pair of links, forming the next successive pair of links, and unfolding the second link of the second-mentioned pair of links in a manner to arrange the links of the second-mentioned pair of links in longitudinal end to end relationship and substantially parallel to the links of the first-mentioned pair of links and simultaneously arranging the links of the third-mentioned pair of links in longitudinal end to end relationship and substantially parallel to the links of the second pair of links.

2. In a method for forming a stuffed sausage 65

casing into a continuous chain of links in which the chain of links is gauged and formed in successive pairs of links, the steps of alternately arranging the successive pairs of links for mounting the chain of links on a smoking support which comprise forming a pair of links and arranging the formed links in longitudinal end to end relationship and longitudinally relative to the line of feed of the stuffed casing, forming the next successive pair of links, folding the last-mentioned pair of links substantially parallel to one another and substantially parallel to the second link of the first-mentioned pair of links, forming the next successive pair of links, unfolding the second link of the second-mentioned pair of links in a manner to arrange the links of the second-mentioned pair of links in longitudinal end to end relationship and substantially parallel to the links of the first-mentioned pair of links and simultaneously arranging the links of the third-mentioned pair of links in longitudinal end to end relationship and substantially parallel to the links of the second pair of links and thereafter passing a smoking support alternately beneath and above the portions of the casing joining the two links of successive pairs of links whereby alternate pairs of the links are supported astride the support and the chain of links is suspended from the support in the form of a continuous diamond-shaped coil.

3. In the method of forming a stuffed sausage casing into a continuous chain of links in which the chain of links is gauged and formed in successive pairs of links for mounting the chain of links on a smoking support which comprises successively forming two successive pairs of links longitudinally of the line of feed of the stuffed casing, folding the second pair of formed links in longitudinal end to end relationship substantially parallel to the links of the first pair of formed links, repeating the operation until the whole of the stuffed casing has been similarly formed and folded into pairs of link lengths, and thereafter passing a smoking support alternately beneath and above the portion of the casing joining the two links of each pair of links whereby alternate pairs of the links are supported astride the support and the chain of links is suspended from the support in the form of a continuous diamond-shaped coil.

4. The method of treating sausage which comprises forming a stuffed sausage casing into a continuous chain of links, arranging the links into a plurality of pairs in which the individual links of each pair are in longitudinal end to end relationship and the pairs are substantially parallel and thereafter passing a smoking support alternately beneath and above the portion of the casing joining the two links of each pair of links whereby alternate pairs of the links are supported astride the support and the chain of links is suspended from the support in the form of a continuous diamond-shaped coil.

WILLIAM JAMES McCUE.
